CONTROL FOR REFRIGERATING SYSTEMS

Glenn Muffly, Scarsdale, N. Y., assignor, by mesne assignments, to Copeland Refrigeration Corporation, Mount Clemens, Mich., a corporation of Michigan

Application December 31, 1928, Serial No. 329,396
Renewed November 25, 1933

1 Claim. (Cl. 62—3)

This invention relates to refrigerating machines and particularly to the control of the flow of refrigerant through the expansion chamber thereof, the principal object being the provision 5 of new and novel means for this purpose.

Another object is to provide a control valve for a refrigerating device comprising a housing through which the refrigerant is adapted to pass, the housing being provided with a metallic bellows therein carrying a valve for controlling the flow of refrigerant through the housing, and the bellows enclosing a gas adapted to be affected by the temperature of the refrigerant in the housing to thereby control the movement of the valve.

Another object is to provide a refrigerant control for a refrigerating system of the direct expansion type comprising a thermostatic element positioned in the suction line from the expansion element.

Another object is to provide, in combination with a refrigerating system of the direct expansion type, an expansion valve for controlling the flow of refrigerant to the expansion element, and a thermostatic element in the suction passage 25 from the expansion element for controlling the flow of refrigerant through the suction passage.

Another object is to provide, in combination with a refrigerating system having an expansion element, a pressure actuated expansion valve for admitting refrigerant to the expansion element, and a thermostatically actuated means on the suction side of the expansion element for controlling the flow of refrigerant from the expansion element.

A further object is to provide, in combination with a refrigerating system of the direct expansion type having a pressure actuated expansion valve of temperature controlled valvular means positioned within the suction line from the expansion element for controlling the flow of refrigerant from the expansion element.

The above being among the objects of the present invention, the same consists in certain features of construction and combinations of parts 45 to be hereinafter described with reference to the accompanying drawings, and then claimed, having the above and other objects in view.

In the accompanying drawings which show a suitable embodiment of the present invention, and in which like numerals refer to like parts throughout the several different views;

Fig. 1 is a more or less diagrammatic sketch of a refrigerating system.

Fig. 2 is a sectional view taken centrally

through an expansion valve for a refrigerating system such as is shown in Fig. 1.

Fig. 3 is a sectional view taken centrally through a control valve for the suction line of a refrigerating system such as shown in Fig. 1.

Fig. 4 is a modified form of the control valve shown in Fig. 3.

Fig. 5 is another modification of the control valve shown in Fig. 3.

I show in Fig. 1 a refrigerating system comprising a compressor 10 which may be driven by an electric motor such as 11 by means of a belt 12. The discharge side of the compressor 10 is connected by a tube such as 13 to a condenser such as 14 which may be cooled either by air or water, and which is connected by a tube such as 15 to a conventional refrigerant receiver 16. The receiver 16 is connected by a tube 17 to an expansion valve indicated generally as 18 in Fig. 1 and which in turn is connected to an expansion element 19 which may take the form of coiled tubes such as shown, or any other suitable construction such as sheet metal.

In conventional constructions the expansion element 19 is connected to the suction side of the compressor 10 by a pipe such as 20 without the interposition of further control means. In the present case a control member indicated generally as 21 in Fig. 1 is inserted in the suction line 20 to the compressor. The control member 21 may take the form shown in Figs. 3, 4 or 5, or any other form constructed in accordance with the teachings thereof.

The operation of the electric motor 11 may be controlled by any suitable type of pressure actuated switch mechanism indicated generally as at 22 which is connected into the suction tube 20 and interposed in the electric circuit 23 between the motor 11 and a suitable source 24 of electrical energy.

The expansion valve 18 which is of the pressure controlled type is shown in detail in Fig. 2 and comprises a body 25 having an inlet passage 26 connected by a small opening 27 to the left hand face of the body 25, as shown in Fig. 2. This face of the body 25 is sealed by a metallic bellows 28 to the head 29 of which is secured a valve member 30 whose head 31 is positioned within the opening 26 and is adapted to close the opening 27 to the passage of the refrigerant upon expansion of the bellows 28. The interior of the bellows 28 is connected by the openings 32, 33 and 34 with the tube 35 which may be a continuation of the expansion element 19 when made of coiled tubes, or may be a separate tube where the ex-

ansion element is of sheet metal or other construction.

It will be obvious that as the pressure builds up in the expansion element 19 such pressure 5 will be transmitted through the passages 34, 33 and 32 to the interior of the bellows 28 and will cause the same to expand and move the head 31 of the valve member 30 to close the opening 27. The particular pressure necessary 10 in the bellows 28 to cause the head 31 to close the opening 27 may be adjustably controlled by rotating the cap 36 threadably received on the body 25 and between the end of which and the head 29 of the bellows is positioned a coil spring 15 37 maintained under compression. Any other form of expansion valve or device adapted to be controlled by pressure within the expansion element to control the flow of refrigerant to the expansion element may be equally well employed 20 in connection with the present invention.

Contrary to conventional practice, I insert in the suction line between the expansion element and the compressor 10 a control valve indicated generally as 21 in Fig. 1 and which may take 25 the form indicated in Fig. 3 which comprises a housing 40 having an inlet passage 41 adapted to be connected to receive refrigerant from the expansion element 19, and which is closed at the other end by a cap member 42 which may thread- 30ably engage the same and may be sealed against leakage by a gasket such as 43 or other suitable means. The cap 42 is provided with a discharge passage 44 through which the refrigerant is adapted to flow to the suction side of the compressor. Within the casing 40 is positioned a metallic bellows 45 preferably provided with a boss such as 46 on one end thereof adapted to be received in a depression such as 47 in the housing 40 so as to hold it in proper relative position 35 with respect to the housing. The opposite end of the bellows 45 is provided with a valve member 48 secured thereto and which is adapted to cooperate with the valve seat 49 formed in the casing 40 to control the flow of refrigerant 40 through the casing 40. A coil spring such as 50 is preferably provided and maintained under suitable compression between the cap 42 and the valve 48 so as to constantly tend to collapse the bellows 45 and move the valve 48 into contact 45 with the valve seat 49 so as to cut off the flow of refrigerant through the housing 40. Lugs such as 51 may be provided on the cap 42 to prevent the valve 48 from opening to such an extent as to cut off the flow of refrigerant through 55 the casing 40. A check valve such as 53 may be provided in cooperative relationship with a valve seat such as 54 for preventing possibility of reversal of flow of refrigerant through the housing 40, if desired, and in such case a stop member such as 55 may be provided for the valve disc 53.

The bellows 45 preferably contains a fluid which may either be the same as the refrigerant employed in the system, or one which will liquefy 60 at a slightly different temperature than the refrigerant employed in the system. The bellows 45 and the housing 40 are so proportioned that when the fluid within the bellows 45 is under a relatively high vapor pressure the valve 48 is in open position with respect to the valve seat 49 so as to permit flow of refrigerant 65 through the casing 40, and when the fluid in the bellows 45 is under a relatively low vapor pressure the bellows 45 is contracted a sufficient 70 amount to permit the spring 40 to seat the valve 75

48 and thereby cut off the flow of refrigerant through the housing 40.

The operation of the above device will be apparent. Considering that the valve 48 is in open position and the compressor 10 is operating, refrigerant from the receiver 16 passes through the expansion valve 18 and enters the expansion element 19 where it turns to gas and then passes through the control valve 21 and through the tube 20 to the suction side of the compressor 10 which acts to reduce the pressure within the expansion element 19. As this action continues the expansion element 19 begins to collect liquid refrigerant therein and the gasified refrigerant passing through the housing 40 decreases in temperature, and some liquid refrigerant may find its way into the housing 40 and become gasified therein, until enough of the fluid within the bellows 45 is liquefied to permit the spring 50 to overcome the pressure in the bellows 45 and 20 close the valve 48. As soon as this happens the expansion element 19 is cut off from the suction side of the compressor and the pressure within the expansion element 19 builds up and causes the expansion valve 18 to close and thus 25 shut off the flow of refrigerant to the expansion element 19. At the same time the pressure in the suction tube 20 drops and this drop in pressure is transmitted to the control device 22 which is thereby actuated to break the circuit 23 between the motor 11 and source of electric energy 24. When a sufficient amount of the refrigerant in the expansion element 19 has been gasified and its temperature rises, a corresponding rise of 30 temperature will occur in the fluid in the bellows 45 which will accordingly expand and force the valve 48 off the seat 49 against the pressure of the spring 50, and thus release the pressure in the expansion element 19 which accordingly 35 will increase the pressure in the suction tube 20 and actuate the pressure switch 22 to start the motor 11, starting another cycle of operation.

In Fig. 4 a modified form of the valve shown in Fig. 3 is illustrated. The valve in this construction is of slightly modified form having a 45 housing 60 provided with an inlet passage 61 which is provided with a bridge as at 62 upon which the bellows 63 is mounted. The bellows 63 is provided with a sheet metal head 64 which also serves as a valve for cooperation with the valve seat 65 to control the flow of refrigerant through the housing 60. A coil spring 66 similar to the spring 50 is provided and maintained under compression between the head 67 for the casing and the recess 68 formed in the head 64 of the bellows 63. The head 67 is of course provided with a discharge passage 69.

In the construction shown in Figs. 3 and 4 the valves are of relatively large diameter and consequently may be more sensitive to the effects of 60 the suction of the compressor than is desirable, and in such cases a construction such as is indicated in Fig. 5 may be employed. The device shown in Fig. 5 comprises a housing 75 having an inlet opening 76 provided with a bridge such as 77 which supports the bellows 78. The opposite end of the housing 75 is enclosed by the head 79 and between the head 79 and the adjacent end of the bellows 78 is positioned a transverse wall 80 having a central opening 80'. The bellows 78 is provided with a head 81 having a stem 82 projecting through the opening 81 in spaced relation with respect to the walls thereof. The stem 82 may be of tubular formation to permit the introduction of the actuating fluid into the bel- 75

lows 78 and may be closed after the introduction of such fluid by a plug 83 of solder or other suitable material. A valve member 84 seated on the end of the stem 82 is constantly urged by the coil spring 85 toward the wall 80 so as to close the opening 80' to the flow of refrigerant. When the actuating fluid in the bellows 78 liquefies, the pressure of the spring 85 forces the valve member 84 against the wall 80 and thus closes the passage 80' to the flow of refrigerant, and when the fluid within the bellows 78 gasifies it causes the bellows 78 to expand and force the valve member 84 away from the wall 80 and permits the flow of refrigerant through the opening 80' into the interior of the head 18 from which it may escape to the compressor through the passage 86. The valve 84 in this construction is of course of materially smaller diameter than the valve shown in Figs. 3 and 4 and therefore is not affected by the suction of the compressor to the extent that the valves shown in those figures are affected.

Another feature of the present invention is that the above described system of control is particularly adaptable for refrigerating systems in which a plurality of expansion units are connected in parallel with a single compressor or other pressure device. This is illustrated in Fig. 1 which shows a second expansion element 90 having an expansion valve indicated generally as at 91 and a suction control valve indicated generally as at 92 inserted between the tubes 17 and 20 in parallel with the expansion element 18. Any number of expansion elements may, of course, be connected in parallel as shown, each with its individual expansion valve and individual suction control valve. The expansion valve 91 may of course be of the same construction as the expansion valve 18 shown in detail in Fig. 2, and the suction control valve 92 the same as the suction control valve 21, except that in the use of the multiple expansion elements it is preferable that the suction control valves all be equipped with a check valve 58, or at least all of the suction control valves except that or those which are employed on that expansion element regulated to obtain the highest minimum temperature of the entire number of expansion elements employed. The suction control valves shown in Figs. 4 and 5 may of course, be provided with check valves in accordance with the teachings of the construction shown in Fig. 3.

Where one or more expansion elements such as the elements 18 and 90 thus described are employed in parallel, it is often desirable that the minimum temperature which is desired in connection with one of the elements is different from the minimum temperature desired in the other of the elements, and it is also necessary for satisfactory operation that the compressor or compressing device be started in operation as soon as the rise in temperature in any of the expansion elements has reached a predetermined value. It is also desirable that should any one of the expansion elements be in condition not to require the introduction of additional liquid refrigerant at the same time that another one of the elements does require the introduction of such refrigerant, that the operation of the compressor should not affect the former. All of these points are taken care of in the construction shown.

For the purpose of illustration, it may be assumed that the expansion valve 18 is set to produce a lower minimum temperature in the ex-

pansion element 18 than the expansion valve 91 for the expansion element 90. Considering that the motor 10 and compressor 11 are operating and both expansion valves 18 and 91 are open so as to deliver liquid refrigerant to the expansion elements 18 and 90 respectively, it will be apparent that the expansion element 18 will be the first to reach its minimum temperature, at which time both the suction control valve 21 and the expansion valve 18 will close, but the compressor 10 will continue to operate until the expansion element 90 has reached its minimum temperature, at which time the valves 92 and 91 will close and a sufficiently low pressure will be produced in the suction tube 20 to cause operation of the control unit 22 to open the circuit 23 for the motor 11.

It will also be apparent that under ordinary conditions the expansion element 18 will be the first of the two expansion elements in which the temperature of the refrigerant will reach the desirable maximum temperature, and thus open its suction control valve. Considering that this is to be the case and that the suction control valve 21 will open while the suction control valve 92 remains closed, the pressure in the suction tube 20 will immediately rise and cause actuation of the control device 22 to again start the motor 11 and compressor 10.

Inasmuch as the control valves 91 and 92 are considered as being closed at this point of operation, the compressor 10 will be acting to refrigerate the expansion element 18 only. In this manner the compressor is caused to operate whenever either of the units 18 or 20 reaches its desired maximum temperature. Inasmuch as each of the suction control valves is provided with a check valve such as 58 as shown in Fig. 3, the gas from the expansion element whose suction control valve has been opened, is prevented from flowing into any of the other expansion elements because of the check valve in the suction control valve for such other elements. In this manner any number of expansion elements may be connected in parallel and each regulated to produce a different minimum temperature in such a manner that each will operate as though it alone were connected to the compressor, and will result in the same satisfactory operation as though such were the case.

Formal changes may be made in the specific embodiment of the invention described without departing from the spirit or substance of the broad invention, the scope of which is commensurate with the appended claim.

What I claim is:

In a refrigerating system of the compression-expansion type, in combination, a pressure imposing element, a plurality of expansion elements connected in parallel between the suction and discharge sides of said pressure imposing element, an individual pressure actuated expansion valve for each of said elements, at least two of said valves being set to effect different minimum temperatures of their corresponding expansion elements, and an individual check valve for each of said expansion elements, except for that or those operating to produce a maximum temperature of the corresponding expansion element or elements, said check valve being located on the discharge side of said expansion elements.

GLENN MUFFLY.
